UNITED STATES PATENT OFFICE

140,470

DESIGN FOR A SHOULDER BAG OR SIMILAR ARTICLE

Edward J. Biel, Brookline, Mass.

Application December 30, 1943, Serial No. 112,125

Term of patent 7 years

(Cl. D87—3)

To all whom it may concern:

Be it known that I, Edward J. Biel, a citizen of the United States residing at Brookline, in the county of Norfolk and State of Massachusetts, have invented a new, original, and ornamental Design for a Shoulder Bag or Similar Article, of which the following is a specification, reference being had to the accompanying drawing, forming part thereof.

Fig. 1 is a front elevational view of a shoulder bag or similar article showing my new design;

Fig. 2 is a rear elevational view thereof with the shoulder straps shown broken away for convenience of illustration;

Fig. 3 is an end elevational view of Fig. 2.

I claim:

The ornamental design for a shoulder bag or similar article, as shown.

EDWARD J. BIEL.
